CLAIM

The ornamental design for an interactive product display, as shown and described.

DESCRIPTION

FIG. 1 is a front, top, and side perspective view of a first embodiment of an interactive product display embodying my new design.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof.

FIG. 8 is a front, top, and side perspective view of a second embodiment of an interactive product display embodying my new design.

FIG. 9 is a front view thereof.

FIG. 10 is a back view thereof.

FIG. 11 is a left side view thereof.

FIG. 12 is a right side view thereof.

FIG. 13 is a top view thereof; and,

FIG. 14 is a bottom view thereof.

Broken lines are used to illustrate features of the interactive product display which form no part of the claimed design. In the second embodiment, broken lines showing the bottom plate form no part of the claimed design. In the second embodiment, each of the legs is shown with a symbolic break in its length. The appearance of any portion of the article between the break lines forms no part of the claimed design.
